UNITED STATES PATENT OFFICE.

ARTHUR N. MCGRAY, OF BOSTON, MASSACHUSETTS.

SHIP'S LOG.

SPECIFICATION forming part of Letters Patent No. 651,260, dated June 5, 1900.

Application filed October 24, 1899. Serial No. 734,676. (No model.)

To all whom it may concern:

Be it known that I, ARTHUR N. MCGRAY, of Boston, in the county of Suffolk, Commonwealth of Massachusetts, have invented a new and efficient Electrically-Operated Ship's Log, 5 of which the following is a specification.

The object of my invention is to obtain a ship's log that will open and close an electric circuit between the log and the vessel while 10 the log is being drawn through the water by the vessel to which the log is connected by a long cable, the purpose of which is to operate devices or mechanisms on board of the vessel to record and indicate the time and distance 15 the vessel has traveled, which I attain in the following manner.

Figure 1 is a longitudinal sectional view of my invention, and Fig. 2 is a diagram illustrating my invention in electrical circuit with 20 a mechanism on board of a vessel to indicate and record the time and distance the vessel has traveled.

A represents the cylindrical shell of my log, which is made up or consists of the association 25 of the following portions: the back end portion a, which is provided with the shaft-passage a', the shaft-bearing recess a², and the rod-guide pocket a³; the intermediate portion a⁴, which is provided with the opening a⁵ through its side for the purpose to admit examination of the interior of the log, the left-hand end of this portion being brazed fixedly to the end of the back end portion in the manner as shown in Fig. 1; the front 30 end portion a⁶, which is provided with the internal threaded portions a⁷ and a⁸ and the flared or beaded end a⁹, the left-hand end of the front end portion and the right-hand end of the intermediate portion butting each 35 other and being brazed fixedly to the partition portion, as clearly shown in Fig. 1, which will be fully described hereinafter, and the back end outer covering portion a¹⁰ and the front end outer covering portion a¹¹, which respectively 40 cover the ends of the back end portion, the intermediate portion, and the front end portion, and to which the said outer covering portions are brazed for the purpose to attain a strong and stiff log shell or case. The inner 45 ends of these outer covering portions are apart from each other, as clearly shown in Fig. 1, for the purpose to admit the placing

over the intermediate portion the movably-fitted inspecting portion a¹², to move between the said outer covering portion's respective 55 ends. This inspecting portion is provided with the inspecting-opening a¹³ therethrough, similar to the inspection-opening in the intermediate portion, and this log shell or case is provided with the steadyng-vane a¹⁴, fixedly a part thereof.

a¹⁵ represents a longitudinal opening in the upper part of the vane sufficient in length so as to prevent the log-inspecting portion contacting the vane for the purpose of attaining 65 an efficient rotary or otherwise movement of the inspecting portion, as may be desired.

B denotes the log-cable, which passes through the end of the front end portion of the log and has its end firmly secured to the 70 vertical disk C. This disk is provided with the arm c and has firmly secured thereto the electric contact-point c', which is insulated from the disk in the following manner:

c² represents a non-conductive washer 75 which is designed to partially pass through the disk, and c³ is a similar washer designed to contact the disk on the opposite side of the disk relatively opposite the first-mentioned washer. Through these washers passes 80 the stem of the screw c⁴, that enters in the contact-point in threaded engagement therewith and positions firmly the contact-point by being drawn against the non-conductive washer, and it (the washer) against the disk, 85 and the opposite washer in like manner by the turning of the screw, which when the contact-point is firmly positioned is set so as to not turn and become fixed. To the disk-arm is fulcrumed or pivoted the lever c⁵, the 90 upper arm of which is provided with the non-conductive cap c⁶ at its end, and the lower arm contacts the disk contact-point.

c⁷ denotes a spring which has its ends respectively connected to the lower arm of the 95 lever and to the disk for the purpose to keep the lower arm against the contact-point.

c⁸ and c⁹ are electric wires. The former is connected to the disk, and the latter is connected to the contact-point. These wires are 100 properly insulated and pass through the log-cable for its entire length.

D represents rubber packing which is designed to surround the log-cable and used to

prevent water entering within the log at its front end. This rubber packing is slipped or passed onto the cable until its vertical end contacts the disk. Then the opposite 5 end of the cable is passed through the end of the front end of the log and drawn through until the conical end of the rubber packing engages the conical sides of the front end of the log. Then the threaded ring *d* is turned 10 in threaded engagement with the front end log portion, as shown, by which the disk is caused to force inward and compress the rubber packing in such a manner that the several parts contacting the rubber packing are 15 firmly gripped and this interior end of the log efficiently packed.

E denotes an outside covering used to insure against water entering the front end of the log. The ends of this covering are 20 respectively secured to the cable and to the end of the log, as shown in Fig. 1.

F represents a vertical disk, and *f* a threaded ring in threaded engagement with similar threads provided on the front end log portion above referred to, and *f'* rubber packing fitted in the annular shoulder *f*² of the front end portion of the log. This vertical disk is provided with the beaded projection *f*³ and the rod-opening *f*⁴ and is forced hard against 30 the rubber packing to effect the impossibility of water entering the chamber *G*.

The partition portion *H* of the log-case is provided with the beaded projection *h*, the rod-guide opening *h'*, and reverse-threaded- 35 screw-shaft bearing *h*².

I denotes the horizontal lever-actuating rod, which is supported and guided by the pocket *a*³ in the back end portion, the partition portion of the log, and the disk *F*, and which 40 has secured to its right-hand end the non-conductive tip *i*.

i' and *i*² are rubber sleeves which have their respective ends efficiently secured to the actuating-rod and to the respective bead- 45 ed projections on the log-partition and disk portions above mentioned, so as to efficiently prevent water passing through the rod-openings *h'* and *f*⁴.

*i*³ represents a collar which is fixed to the 50 lever-actuating rod near its right-hand end.

J denotes a spring which has one end connected to the vertical wall of the log-back end portion and the other end connected to the actuating-rod, the purpose of which is to 55 keep the actuating-rod out of contact with the lever *c*⁵ when the rod is not being actuated by the reverse-threaded-screw-shaft finger-carriage, (represented by the letter *K*.) This carriage is loosely fitted to the lever-ac- 60 tuating rod, so as to freely move back and forward thereon.

k denotes the worm-finger, which meshes with the screw-shaft threads and is movably fitted to the carriage.

65 *L* represents a lignum-vitae ball-bearing bushing which is fitted in the shaft-bearing

recess of the back end portion of the log-case in a fixed manner.

M denotes antifriction-balls, and *N* a lignum-vitae collar fixedly secured to the worm-shaft. This collar has the reduced portion *n*, which, together with the inner surface of the bushing, produces the antifriction-ball race-way *n'*.

O represents the reverse-threaded screw-shaft, which is supported at one end by the ball-bearing just described and at the other end by the bearing provided on the partition portion of the log-case. To the outer end of the screw-shaft is rigidly secured the eye *o*. 70 *o'* denotes the threads on the shaft.

P represents a rotator, and *p* the rotator-rope, which has one end secured to the rotator and the other end secured to the eye of the reverse-threaded screw-shaft, as is shown 80 in the drawings, Fig. 2.

In the diagram Fig. 2, 1 represents batteries in the electric circuit of the log. 2 denotes the vessel, and 3 an electrically-actuated mechanism on board of the vessel in 90 electrical circuit with the log for the purpose to indicate and record the time and distance the vessel has traveled.

I will now describe the use and operation of the log. While the vessel is traveling the 95 log is cast overboard and allowed to free the stern of the vessel for about two hundred and fifty or three hundred feet and is drawn through the water by being secured to the end of a cable let out from on board the vessel to which the other end of the cable is secured. As soon as the log becomes drawn 100 through the water its rotator revolves and the rotator revolves the rotator-rope, and it in turn rotates the reverse-threaded screw-shaft 105 of the log, and the screw-shaft moves the screw-shaft-finger carriage on its guideway, the direction of the movement of which is shown in Fig. 1 to be toward the front of the log about to contact the dog or collar on the lever-actuating rod, which also acts as the carriage-guideway. As the carriage is further 110 moved forward it contacts the collar and moves forward the lever-actuating rod, which so contacts the circuit breaking and closing 115 lever as to cause its lower arm to swing out of contact with the electric contact-point. This breaks the circuit between the log and the mechanisms on board the vessel, which causes the electrically-operated mechanisms to operate in such a manner to record the time the circuit was broken and to indicate the distance the vessel has traveled—the purpose for which they are designed.

In the meantime the carriage is caused to move in the opposite direction by the screw-shaft, owing to the threads being right and left handed thereon, as is shown in Fig. 1, and the actuating-rod is drawn back simultaneously by the spring connected thereto, which frees the circuit-lever, so as to close the circuit again until 120 broken by the return of the carriage, which 125 130

has to travel near the entire length of the screw-shaft and return before the circuit is again broken. The distance that the carriage has to travel before it breaks the circuit is measured in time to either equal one-eighth, one-tenth, or one-twelfth of a mile that the vessel has traveled or any fractional part of a mile, as the log may be designed for—that is to say, the distance that the carriage travels before it again breaks the circuit is equal to a fractional part of a mile that the vessel has traveled.

The course of the electric current is from the vessel through the indicating and recording mechanisms, along the electric wire through the log-towing cable that protects the wire, through the disk-circuit lever-supporting arm over the circuit-lever, and through the contact-point and over the return-wire to its point of beginning. Both electric wires pass through and are protected by the towing-cable, and the course of the electric current may be the opposite to that just described without making any material difference in its action.

Q and G represent hermetically-sealed compartments or chambers, the purpose of which is to prevent water entering the chamber G, and thus short-circuiting the electrical connections.

R denotes the reverse-threaded-screw-shaft chamber.

Having described my invention, I claim—

1. A ship's log comprising an electrical circuit-breaker, a reverse-threaded screw-shaft revolving by a rotator, and means in contact with said screw-shaft for actuating the said circuit-breaker.

2. A ship's log comprising an electrical circuit-breaker, a reverse-threaded screw-shaft revolving by a rotator, and means in contact with said screw-shaft for actuating the said circuit-breaker, and the log-casing designed to prevent short-circuiting of the parts within.

45 3. A ship's log consisting of a cylindrical shell having steadyng-vanes, a towing-cable firmly secured to the front end of the log, two hermetically-sealed compartments in the front end of the log, a spring-pressed circuit

50 breaking and closing lever and a contact-point supported and positioned in electrical association with each other within the first front-end compartment, two insulated electric wires within the towing-cable for its en-

55 tire length, one wire in circuit with the circuit breaking and closing lever, and the other wire in circuit with the contact-point, and the

wires, the lever, and the contact-point efficiently insulated from the other parts of the log, means in operative association with a reverse-threaded screw-shaft and the interior of the log-shell adapted to swing the circuit breaking and closing lever out of contact with the contact-point, a reverse-threaded screw-shaft, and suitable bearings to support the reverse-threaded screw-shaft, and a rotator efficiently secured to the outside end of the reverse-threaded screw-shaft, substantially as, and for the purpose described.

4. A ship's log consisting of a cylindrical shell having steadyng-vanes, a towing-cable firmly secured to the front end of the log, two hermetically-sealed compartments in the front end of the log, a spring-controlled circuit breaking and closing lever and a contact-point supported and positioned in electrical association with each other within the first front-end compartment, two insulated electric wires within the towing-cable for its entire length, one wire in circuit with the circuit breaking and closing lever, and the other wire in circuit with the contact-point, and the wires, the lever, and the contact-point efficiently insulated from the other parts of the log, a horizontal rod supported in guideways and passing through the vertical walls of the hermetically-sealed compartments, and having its end close to and opposite the arm of the circuit breaking and closing lever, and a non-conductive cap fitted to said end of the rod, flexible and waterproof sleeves having their ends respectively hermetically secured to the said walls and to the horizontal rod, a spring connected to the log-shell and to the rod so as to make the normal position of the rod out of contact with the circuit breaking and closing lever, a shipping-collar secured to said rod, a carriage, a carriage-guideway, a reverse-threaded-screw-shaft finger movably fitted to the carriage and in mesh with a reverse-threaded screw-shaft, the reverse-threaded screw-shaft, suitable bearings provided on the log-case to support the reverse-threaded screw-shaft, and a rotator efficiently secured to the outside end of the reverse-threaded screw-shaft, substantially as described.

In testimony whereof I have hereunto set my hand to this application this 21st day of October, 1899.

ARTHUR N. MCGRAY.
